(57) **CLAIM**

The ornamental design for a display device for hardness
tester, as shown and described.

DESCRIPTION

FIG. 1 is a front, right-side, top perspective view of the
display device for hardness tester;
FIG. 2 is a front elevational view thereof;
FIG. 3 is a top plan view thereof;
FIG. 4 is a right-side elevational view thereof;
FIG. 5 is a left-side elevational view thereof;
FIG. 6 is a rear elevational view thereof;
FIG. 7 is a bottom plan view thereof; and,
FIG. 8 is a rear, left-side, top perspective view.
The broken lines depict unclaimed parts of the display
device, and thus form no part of the claimed design.

1 Claim, 8 Drawing Sheets
